UNITED STATES PATENT OFFICE.

SOLOMON MONOSON, OF NEW YORK, N. Y.

HEADWEAR.

978,048.

Specification of Letters Patent.

Patented Dec. 6, 1910.

Application filed April 5, 1910. Serial No. 553,664.

To all whom it may concern:

Be it known that I, SOLOMON MONOSON, a citizen of the United States, and a resident of the borough of Manhattan, in the city of New York, county and State of New York, have invented a new and useful Article of Headwear, of which the following is a specification.

My invention relates to an improvement 10 in head-wear, and has for its object the provision of an article of head-wear adapted for use in any one of several different arrangements, thus giving a large variety of appearances to one and the same article.

The invention consists in an article of 15 manufacture of head-wear having a pliable crown and a pliable brim, united at the base of the crown, and provided with certain useful features, as hereinafter more particularly described and more particularly pointed out in the appended claims.

The invention is embodied in the cap or 20 hat made of fur, illustrated in the accompanying drawing, forming part hereof, in 25 which—

Figure 1 is a vertical, sectional view 30 through the middle of the cap; Fig. 2 is an elevation, partly in section and partly broken away, of the same; and Figs. 3, 4, 5, 35 and 6 are perspective views illustrative of the various arrangements of the cap or hat.

In the drawing the reference symbol C 40 designates the crown, and B, the brim. The brim and crown are secured together at the 45 base b of the crown by stitching or in other suitable manner, and the band forming the brim is doubled in underneath and its edge e is carried back to substantially the line of 50 union of the brim and the crown, such edge e being stitched to a substantially non-stretchable band b', preferably of velvet, and such band b' being stitched to the crown, or 55 the brim, or both, at the base b, the reference s indicating the stitch aforesaid. A vizor or peak V is attached to a felt or other 60 wadding w placed between the two thicknesses of material forming the brim B, by threads t. This vizor or peak may be of leather, two or more ply buckram, or other 65 suitable stiff but flexible material. The lining L is attached to the band b' as by stitching. A draw-band or cord D is secured to 70 the lining L between it and the crown C by looped thread t so that it may be drawn 75 through such loops to vary the size of the cap to suit the head of the wearer, a loop d

of said draw band D being taken through a hole in the lining to the inside thereof in position convenient for the fingers to grasp it and operate said draw band D.

A substantially non-stretchable band or 80 tape b² is placed within the brim, between the outer and inner thickness O, I, thereof, at the fold and is there secured, as by stitching.

The flexible but substantially non-stretchable bands b', b² permit the hat or cap to 85 be folded into compact form while preventing it from being stretched out of shape, and the band b² permits the brim B to be folded up 90 as shown in Fig. 3, that is, permits the hat or cap to be telescoped; the vizor to be turned down as shown in Fig. 4; or the vizor to be elevated as shown in Fig. 5 95 while the remainder of the brim is turned down, as in protecting the ears and the back of the neck against cold.

Fig. 6 shows a crease c in the crown, as 100 in the Alpine hat or cap. It is obvious that such crease can also be used with the other arrangements of vizor and brim shown.

What I claim as new and desire to secure by Letters Patent of the United States is—

1. As an improved article of manufacture, 105 an article of head-wear consisting of a pliable fur crown and a pliable fur brim joined directly together at the base of the crown forming a continuous unbroken external fur surface with the brim doubled back on itself underneath substantially to the line joining brim and crown, a substantially non-stretchable band to which the edge of the doubled-back brim is attached and which band is attached to the inside of the article substantially at such joining line, and a vizor or peak within and concealed by the doubled brim.

2. As an improved article of manufacture, 110 an article of head-wear consisting of a pliable crown and a pliable brim joined together at the base of the crown forming a continuous unbroken external fur surface with the brim doubled back on itself underneath substantially to the line joining brim and crown, a substantially non-stretchable band to which the edge of the doubled-back brim is attached and which band is attached to the inside of the article substantially at such joining line, a substantially non-stretchable band secured within the brim at the doubling thereof, and a vizor or peak within and concealed by the doubled brim.

3. As an improved article of manufacture, an article of head-wear consisting of a pliable crown and a pliable brim joined together at the base of the crown with the 5 brim doubled back on itself underneath substantially to the line of joining of brim and crown, a substantially non-stretchable band to which the edge of the doubled-back brim is attached and which band is attached to 10 the inside of the article substantially at such

line of joining, a lining attached to said band, a draw band between the lining and the crown and extending within the lining, and a vizor within and concealed by the doubled brim.

SOLOMON MONOSON.
